Primary Examiner—Melody N. Brown
Attorney, Agent, or Firm—Richard C. Litman[57] **CLAIM**

The ornamental design for an adjustable spacer/stabilizer for a bike rack, as shown and described.

DESCRIPTION

FIG. 1 is a perspective view of an adjustable spacer/stabilizer for a bike rack showing my new design mounted on a bike rack which, in turn, is mounted on the trailer hitch of a pickup truck;

FIG. 2 is a perspective view similar to FIG. 1 but showing the invention mounted on a bike rack which, in turn, is mounted on a motorcycle;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top view thereof; and,

FIG. 8 is a bottom view thereof.

The broken line showing of portions of a truck and motorcycle in FIGS. 1 and 2, respectively, and a bike rack in FIGS. 1 and 2 is for illustrative purposes only and forms no part of the claimed design.
